UNITED STATES PATENT OFFICE.

RALPH C. IDONE, OF CLEVELAND, OHIO.

HAT-PIN.

1,261,816.

Specification of Letters Patent.

Patented Apr. 9, 1918.

Application filed August 27, 1917. Serial No. 188,345.

To all whom it may concern:

Be it known that I, RALPH C. IDONE, a citizen of the United States, residing at Cleveland, in the county of Cuyahoga and State of Ohio, have invented certain new and useful Improvements in Hat-Pins, of which the following is a specification.

My invention relates to improvements in hat-pins, and more particularly to that class 10 or type known as "anchored" hat-pins, the object being to provide means whereby the hat-pins, when placed in its hat securing position, will be securely retained in such position as against accidental removal or 15 displacement.

The primary object of the invention is to provide a generally improved hat-pin of this class, which will be exceedingly simple in construction, cheap of manufacture, and efficient in use.

A further object is the provision of enlarged hat-engaging anchor portions or convolutions at the base of the pointed portion of the hat-pin adapted to engage or interlock with the second or opposing wall of the hat crown, after being inserted and passed through the initial or first wall thereof and through the hair of the wearer in position, and providing simple and convenient 20 means for the ready insertion and removal of the hat-pin when in use.

With the above mentioned and other ends in view, the invention consists in the novel construction, arrangement, and combination 25 of parts, hereinafter described, illustrated in some of its embodiments in the accompanying drawings, and particularly pointed out in the appended claims.

Referring to the drawings, forming a part 30 of this specification, Figure 1, is a view of the improved hat-pin in its anchored or securing position in the crown of an ordinary hat.

Fig. 2, a side elevation of a hat-pin constructed in accordance with this invention.

Fig. 3, a similar view of a further modified form of same.

Fig. 4 a view of the pointed portion of a hat-pin body or shank, of angular or 50 square shape in cross section, before being twisted to form the spiral shaped anchor convolutions shown in Fig. 5.

Fig. 5 a view of a complete hat-pin formed from the angular form of shank shown in 55 Fig. 4, and illustrating the spirally arranged anchor convolutions thereon.

Fig. 6 a view of a still further modified form, the anchor convolutions being spirally arranged.

Fig. 7 a view of a modification of the form 60 shown in Figs. 1, and 2, the convolutions in this instance extending on the same side and being connected by an intermediate hat-engaging notch or recess.

Similar numerals of reference designate 65 like parts throughout all the figures of the drawings.

The improved hat-pin shank or body 1, may be of the usual round or cylindrical form as shown in Figs. 1 to 3, inclusive, and 70 Figs. 6 and 7, of the drawings, or if desired, may be of square or angular shape in cross section as shown in Figs. 4 and 5, of the drawings.

The improved hat-pin may be provided 75 with any suitable and convenient form of head 2, and is preferably provided with a gradually tapered or pointed portion 1^a.

As a convenient means of securing or anchoring the pointed or tapered portion of 80 the hat-pin in the second or opposing wall of the crown of the hat 3, after being initially inserted and passed through the first wall of the hat, and through the hair of the wearer as indicated in Fig. 1, of the drawings, the pin is provided with enlarged hat-engaging anchor portions or convolutions 1^b, said anchor portions or convolutions 1^b, being preferably formed at the base of the tapered portion 1^a, and relatively near the 85 tip of such tapered portion 1^a, as shown in all the figures of the drawings.

It will be observed that the hat-engaging or anchored convolutions extend beyond the planes of the pin body or shank 1, or in 90 other words, are larger in cross section than the shank of the pin so that when the second wall of the hat is impaled over one or more of the anchor convolutions the pin will be securely anchored or secured within the 95 crown of the hat.

In the form shown in Figs. 1, and 2, of the drawings the anchor convolutions 1^b, extend in a common plane on opposite sides of the pin body in serpentine form thus forming 100 hat-engaging notches or recesses, while in the form shown in Fig. 7, such convolutions extend in a common plane at one side only of the pin body and are connected by means of an intermediate hat-engaging 105 notch or recess 1^c.

In the form shown in Fig. 6, of the draw-

ings, the convolutions 1^b, are spirally arranged as distinguished from the form shown in Figs. 1, 2, and 7, of the drawings.

In the form shown in Fig. 3, of the drawings, the spiral arrangement of the convolutions 1^b, may be secured in the process of manufacture by simply twisting the tapered or pointed end 1^a, in a well known and understood manner, and likewise as to the form shown in Fig. 5, of the original angular or square form of the pin, this form being particularly adapted to form the spiral form shown in Fig. 5.

In the act of inserting and securing the hat-pin in the hat it is obvious that after being first passed through the first or initial wall of the hat, and upon entering the second or opposite wall of the hat, the anchor portions or convolutions will offer some resistance to the final passage of these portions of the hat-pin and such resistance to the free passage of the hat-pin will readily enable and determine the securing of the pin, and as to the spiral forms shown in Figs. 3, 5, and 6, of the drawings it is obvious that the pin may be readily inserted or removed by giving one or two turns or revolutions of the pin in the final securing or disengagement of the spiral form of anchor in the other or opposite wall of the hat.

From the foregoing description, taken in connection with the accompanying drawings, the operation and advantages of my invention will be readily understood.

Having thus described some of the embodiments of my invention what I claim and desire to secure by Letters Patent, is,—

1. A hat-pin having a substantially straight shank throughout the major portion of its

length and terminating at one end in corrugations and a tapered point, said corrugations adapted to retain said pin in the hat when inserted therein.

2. A hat-pin having a straight shank corresponding approximately to the diameter of the hat, and having a tapered point and corrugations at one end and a head at the other whereby said pin is normally retained in the hat.

3. A hat-pin, comprising a head and a tapered point, and a straight portion extending from said head toward said point and provided with corrugations adjacent to the latter, whereby when said pin is inserted in the hat the same is secured at one side and prevented from being withdrawn from the opposite side of the hat when withdrawn from the hair of the wearer.

4. A hat-pin, comprising a head and tapered point, and a straight portion corresponding approximately to the diameter of the hat and provided with serpentine corrugations adjacent to said tapered point, whereby when said pin is inserted through one side of the hat and the hair of the wearer and into the opposite side the same is secured in the latter by said corrugations, and when withdrawn from the hair of the wearer said corrugations will engage with the opposite or first side of the hat and prevent the entire withdrawal of the pin from the latter.

In testimony whereof I have affixed my signature in the presence of two witnesses.

RALPH C. IDONE.
